UNITED STATES PATENT OFFICE.

DANIEL J. GOLDEN, OF BROCKTON, MASSACHUSETTS.

ATHLETIC SHOE.

Application filed July 14, 1924. Serial No. 725,755.

To all whom it may concern:

Be it known that I, DANIEL J. GOLDEN, citizen of the United States, residing at Brockton, in the county of Plymouth and 5 State of Massachusetts, have invented new and useful Improvements in Athletic Shoes, of which the following is a specification.

This invention relates to shoes for use by 10 players of baseball and other athletic games, provided with ground-engaging cleats or spurs projecting outward from the tread surfaces.

The object of the invention is to provide 15 an improved construction providing for the secure attachment of the cleats to the shoe in such manner that the cleats are firmly supported against tipping and endwise displacement, without obstruction of the tread surface between the cleats by cleat-attaching 20 protuberances liable to retain mud, the cleats being secured independently of each other, so that there are no cleat-securings 25 instrumentalities on the tread surface extending from cleat to cleat and liable to be broken by flexure of the tread surface.

I attain this and other related objects by the improvements hereinafter described and claimed.

Of the accompanying drawings forming 30 a part of this specification,—

Figure 1 is a bottom plan view of a shoe embodying the invention.

Figure 2 is a section on line 2—2 of Figure 1.

Figures 3 and 4 show separately the structures shown assembled by Figure 2.

Figure 5 is a perspective view of one of the reinforcing plates shown by Figures 1, 2 and 3.

Figure 6 is a perspective view of one of the cleats.

Figure 7 is a bottom view of one of the tread members.

The same reference characters indicate 45 the same parts in all of the figures.

The preferred construction of a shoe embodying the invention, includes a sole 12 and an upper 13. These parts may be assembled and connected in any suitable manner prior to the application of the tread members and outer shank portion herein-after described, the arrangement being such that the outer surface of the sole is entirely outside the upper. 14 designates a fore 55 part tread member formed, in this instance,

as a tap. 15 designates a heel tread member formed as a heel lift. The members 14 and 15 are preferably of sole leather and each is provided with a plurality of orifices 16 arranged as shown by Figure 7. The 60 tread members are preferably connected by a shank portion 17 of more flexible leather united to the adjacent ends of the tread members by suitable fastenings such as 65 stitches 18.

In the orifices 16 are inserted screw-threaded shanks 19 formed on cleats or spurs 20 which project from the tread face. The cleats are provided with bases 21 bearing on the outer surface of the tread member. To the inner surface of the tread member are fixed by rivets 22 flat anchoring plates 23, which have screw-threaded or tapped orifices coinciding with the orifices 16 and engaged with the shanks 19. The 70 cleats are firmly braced against tipping displacement by the bearing of their bases 21 on the outer surface of the tread member 14 and by the engagement of their shanks 19 with the anchoring plates 23. Owing to the 75 described construction, the portion of the tread face between the cleats is free from protuberances liable to retain mud in the spaces between the cleats. This feature 80 particularly commends the shoe to base ball players who are freed from the necessity of dislodging mud from said spaces.

To support the cleats and the anchoring members against inward displacement tending to cause an inward bulging of the member 14 and the sole 12, I provide the sole with thin sheet metal reinforcing plates 25 which are of smaller area than the tread members and of larger area than the anchoring plates and are seated on the outer 90 face of the sole 12 in position to support the anchoring plates 23. The reinforcing plates are laid upon the sole 12 before the tread members are applied, and are preferably provided with spurs 26 which are 95 forced into the sole to prevent edgewise displacement of the plates.

The tread members 14 and 15 and the shank portion 17 may be secured to the superstructure covered thereby by fastenings, such as stitches 27, uniting the fore 105 part tread member 14 and the shank portion to corresponding portions of the superstructure, and nails 28 uniting the heel member 15 to other portions of the super- 110

structure. Any other or additional fastenings may be employed, such as rivets 29 shown by Figure 1.

The anchoring plates 23 have extended 5 bearing on the reinforcing plates 25 and on the inner surfaces of the tread members, so that the reinforcing plates, which are of much larger area than the anchoring plates, prevent tipping movements of the anchoring plates, while the anchoring plates and the bases 21 of the cleats prevent tipping movements of the cleats on the tread members.

It will be seen that the anchoring plates 15 23 are wholly on the inner surfaces of the tread members and do not project into the orifices 16 thereof. The area of the cleat bases 21 is such that they constitute clamping bases bearing on the outer surfaces of 20 the tread members around the orifices 16, and acting, when the shanks 19 are screwed fully in, to compress the portions of the tread members in which the orifices are formed, so that the walls of the orifices are 25 pressed against the threaded shanks 19 and prevent accidental unscrewing rotation of the latter.

I claim:

An athletic shoe comprising a sole and an 30 upper connected thereto, the outer surface of the sole being entirely outside the upper,

a flexible reinforcing plate secured to the outer sole and seated on the outer surface thereof, an apertured tread member secured to the sole and having orifices extending 35 from its outer to its inner surface, flat anchoring plates seated on the inner surface of the tread member and riveted to the latter, said plates bearing on the reinforcing plate and being provided with tapped orifices coinciding with the orifices in the tread member, and cleats having threaded shanks 40 inserted in the orifices of the tread member and engaged with the tapped orifices of the anchoring plates, said cleats having clamping bases bearing on the outer surface of the tread member around the orifices in the latter and compressing the portions of the tread member in which said orifices are 45 formed, so that the walls of the orifices are 50 pressed against the threaded shanks and prevent accidental unscrewing rotation of the latter, the reinforcing plate preventing tipping movements of the anchoring plates seated thereon, while the reinforcing plate, 55 the anchoring plates and the cleat bases prevent tipping movements of the cleats on the tread member.

In testimony whereof I have affixed my signature.

DANIEL J. GOLDEN.
